PRESSURE GAUGE

Harry W. Hoff, Quakertown, Pa., assignor to Ametek,
Inc., New York, N.Y., a corporation of Delaware

Filed July 12, 1962, Ser. No. 70,901

Term of patent 14 years

(Cl. D52—6)

Fig. 1

Fig. 2

Fig. 3

Fig. 4

FIG. 1 is a front view of a pressure gauge showing my new design, it being understood that the flutes as shown are continued entirely around the surface.

FIG. 2 is a side view of FIG. 1;

FIG. 3 is a front perspective view of the gauge casing; and

FIG. 4 is a fragmentary enlarged sectional view taken along the line 4—4 of FIG. 3.

The essential feature of my design for a pressure gauge resides in the closely spaced flutes on the inner circumference of the side walls of the integral casing.

I claim:

The ornamental design for a pressure gauge, substantially as shown and described.
